UNITED STATES PATENT OFFICE.

FRANK KUHN AND JAY A. HAND, OF DETROIT, MICHIGAN, ASSIGNEES TO AMERICAN ELECTRICAL HEATER COMPANY, OF DETROIT, MICHIGAN, A CORPORATION OF MICHIGAN.

MACHINE FOR MOISTENING ADHESIVE TAPE.

1,276,773.

Specification of Letters Patent. Patented Aug. 27, 1918.

Application filed March 14, 1918. Serial No. 222,287.

To all whom it may concern:

Be it known that we, FRANK KUHN and JAY A. HAND, both citizens of the United States of America, residing at Detroit, in the county of Wayne and State of Michigan, have invented certain new and useful Improvements in Machines for Moistening Adhesive Tape, of which the following is a specification, reference being had therein to the accompanying drawings.

This invention relates to machines for moistening adhesive tape.

In devices of this character it is common to provide for feeding the tape from a reel in such a manner that its coated surface will have contact with a roller partially immersed in water. It has been found, however, that the water if cold does not act rapidly enough to dissolve the adhesive coating so that the tape does not always stick firmly to the surface to which it is applied after being drawn from the machine.

It is the object of this invention to provide means for electrically heating the water applied to the coated surface of the tape so that there will be an increased solvent action on the adhesive resulting in an immediate softening of the coated surface so that the full efficiency thereof may be derived.

In the drawings:

Figure 1 is a view of the machine in side elevation and partial section, the normal position of the tape being shown in full lines and its position when being drawn over the moistened roller being indicated in dash lines;

Fig. 2 illustrates in perspective a modified form of the heater shown in Fig. 1;

Fig. 3 illustrates another modified form of electric heater.

The reference character 1 designates the base of the machine and 2 is a circular casting mounted upon said base and receiving the reel of tape which is adapted to feed therefrom, as indicated at 3, through a slot

4. After engaging a series of guide rollers 5, 6, 7 and 8 the tape 3 is adapted to be

drawn over the roller 9 which is partially immersed in a body of water or other liquid contained by a tank 10. The guide rollers 50 5, 6, 7 and 8 are carried by a frame 11, pivotally mounted as indicated at 12 and adjustable between the positions shown in full lines and dash lines in Fig. 1, the roller 8 being spaced from the roller 9 in the 55 former or normal position and being shifted into contact with said roller 9 in the latter position of said frame to insure rotation of the roller 9.

In the tank 10 there is immersed an electric heater 13, the detailed construction of which is no feature of the present invention, said heater being mounted in an end wall of said tank and having connection exteriorly of the tank with a metallic tube 14 through 65 which the conductors supplying current to the heater are led to a socket member 15.

In the modification illustrated in Fig. 2 the heating element 16 is interiorly secured to the bottom of the tank by bolts or rivets 16^a, while Fig. 3 shows an arrangement wherein the heater 17 is exteriorly secured to the bottom of the tank.

What we claim as our invention is:—

1. The combination with a mounting for a reel of adhesive coated tape, of a tank for receiving a body of liquid, means for applying said liquid to the coated surface of the tape as the latter is drawn from the reel, an electric heater permanently associated with 75 said tank, and a metallic tube extending from said heater exteriorly of the tank and terminally carrying a socket member.

2. The combination with a mounting for a reel of adhesive coated tape, of a tank for receiving a body of liquid, an electric heater immersed within said tank and secured to an end wall thereof, and a tubular metallic receiver for conductors extending to said heater.

In testimony whereof we affix our signatures.

FRANK KUHN.
JAY A. HAND.
